(57) **CLAIM**

We claim the ornamental design for a wearable movement monitor docket station, as shown and described.

DESCRIPTION

FIG. 1 is a top, front perspective view of a wearable movement monitor docket station showing the new design;

FIG. 2 is a top, rear perspective view thereof;

FIG. 3 is a perspective view thereof;

FIG. 4 is a front side view thereof;

FIG. 5 is a rear side view thereof;

FIG. 6 is a right side view thereof;

FIG. 7 is a left side view thereof;

FIG. 8 is a top side view thereof; and,

FIG. 9 is a bottom side view thereof.
